(57) **CLAIM**

The ornamental design for a sports helmet brim, as shown and described.

DESCRIPTION

FIG. 1 is a top, front, side perspective view of a sports helmet brim showing our new design;

FIG. 2 is a front view thereof;

FIG. 3 is a rear view thereof;

FIG. 4 is a side view thereof;

FIG. 5 is a top view thereof; and,

FIG. 6 is a bottom view thereof.

The broken lines shown on the sports helmet brim represent thread stitching. The broken lines illustrating the human in FIGS. 2-4 form no part of the claimed design.

All surfaces not shown form no part of the claimed design.
